UNITED STATES PATENT OFFICE

2,615,584

HYDRAULIC HOIST

Eli J. Adams, Springfield, Mo.

Application April 21, 1950, Serial No. 157,347

4 Claims. (Cl. 212—59)

1

This invention relates to improvements in hydraulic hoists of the type involving a boom which is fixed when in operative position and a hoisting cable system, the primary object of the invention being to provide more efficient and capable devices of this kind in which the fixed boom and a diagonal brace therefor are foldable against the mast, so that the devices are in a compact form and occupy a minimum of space when not in use.

Another important object of the invention is to provide devices of the character indicated above which can be quickly and easily transferred back and forth between a mounting on a highway truck bed and a ground frame or dolly without the use of tools.

A further important object of this invention is to provide devices of the character indicated above having an arrangement of mast, fixed boom and hydraulically operated hoist cable system which provides a straight line lift and which maintains the same power ratio over the entire lifting range.

Other important objects and advantageous features of the invention will be apparent from the following description and the accompanying drawings, wherein, for purposes of illustration only, specific embodiments of the invention are set forth in detail.

In the drawings, wherein like numerals designate like parts throughout the several views:

Figure 1 is a left-hand side elevation, showing a form of the invention involving a ground frame or dolly and a lifting arm;

Figure 2 is a top plan view of Figure 1;

Figure 3 is an enlarged fragmentary transverse vertical section taken on the line 3—3 of Figure 1;

Figure 4 is a fragmentary right-hand side elevation of the mast, showing the hydraulic hand pump;

Figure 5 is an enlarged fragmentary vertical longitudinal section taken through the lower part of the mast and the dolly;

Figure 6 is an enlarged fragmentary vertical longitudinal section taken through the upper part of the mast and the boom;

Figure 7 is an enlarged perspective view of the mast pulley yoke;

Figure 8 is an enlarged horizontal section taken on the line 8—8 of Figure 5;

Figure 9 is a fragmentary side elevation, showing a form of the invention involving a truck frame or bed mounting, the lifting arm being absent, and the boom and the brace being in folded inoperative positions;

2

Figure 10 is an enlarged fragmentary vertical longitudinal section taken on the line 10—10 of Figure 9;

Figure 11 is a top perspective view of the truck mounting tube or socket;

Figure 12 is an enlarged fragmentary horizontal section taken on the line 12—12 of Figure 1;

Figure 13 is a fragmentary vertical longitudinal section taken on the line 13—13 of Figure 12.

10 Referring in detail particularly to Figures 1 to 8 of the drawings, the ground frame or dolly, generally designated 15, is A-shaped in plan and comprises the two forwardly diverging horizontal I-beam legs 16, 16 welded or otherwise suitably secured to the under side of a heavy horizontal base plate 17 of triangular shape and having ground-engaging wheels 18, 18 on their forward ends. The apex portion of the base plate has beneath it a steerable caster wheel device involving an inverted U-shaped body 19 having a vertical spindle 20 journaled through the plate and in a tubular journal 21 rising from the plate. A reclining U-shaped yoke 22 has the forward ends of its arms pivoted at 23 to the lower ends of the arms of the body 19 and has a vertical bar 24 rising from the rearward end surmounted by a transverse handle 25. A ground-engaging wheel 26 has an axle 27 journaled in the arms of the reclining yoke 22 at a point intermediate the pivots 23 and the rearward end of the yoke 22, whereby upon rearward swinging of the bar 24, the wheel 26 is forcibly depressed in engagement with the ground 28, as shown in Figure 5, so as to elevate the fixed feet 29 depending from the rear ends of the I-beam legs 16 out of engagement with the ground, whenever it is desired to move the device over the ground rollably supported on the wheels 18 and 26.

40 The dolly 15 further comprises the socket tube 30 welded or otherwise suitably fixed to rise from a central part of the base plate 17 and having on its upper end an external thrust flange 31. A pair of front diagonal brace plates 33 and a single rear brace plate 34 are secured to extend between the plate 17 and the socket tube 30. The hoisting assembly, which is generally designated 35, comprises the perpendicular mast 36 comprising a pair of vertically elongated parallelly spaced, similar plates 37 to and between whose lower ends is welded a heavy outer tube 38 which depends below the lower ends of the plates 37 and is of an external diameter to fit rotatably in the socket tube 30 and serve as the spindle for the hoisting assembly. Also welded to the lower ends 50 of the mast plates 37 and to the spindle tube 38 is an external flange 39 which rotatably rests

upon the thrust flange 31 on the upper end of the socket 30.

As shown in Figure 5 of the drawings, the spindle tube 38 has a closed lower end 40 to bear upon a portion of the plate 17 exposed by the socket tube 30 and surrounding an access hole 41 provided in the plate 17. Within the spindle tube 38 is seated the hydraulic cylinder 42 with its lower end engaging the closed lower end 40 of the spindle tube and having a breather plug 43 traversing the closed end 40 and accessible through the hole 41. The upper end 44 of the hydraulic cylinder 42 rises above the spindle tube 38 and between the mast plates 37, and a piston rod 45 rises through the upper end 44 and has fixed thereon, as indicated at 46, a U-shaped pulley yoke 47 having the pulley wheel 48 journaled between its arms in vertical alignment with the piston rod 45.

Extending through and between the upper ends of the mast plates 37 in vertical alignment with the pulley wheel 48 is the upper bolt 49 which serves as the pivot for the boom 50, as the axle for the upper mast pulley 51, and as the upper support for the pulley yoke 52. A similar lower axle bolt 53 which carries the lower pulley 54 is offset forwardly from the upper axle bolt to provide clearance behind it for hoisting cable 55.

The mast pulley yoke 52, as shown in Figures 6 and 7, comprises an inverted U-shaped form having spaced depending legs 56 formed with pairs of upper and lower holes 57 and 58, respectively, to pass the upper and lower axle bolts 49 and 53, respectively. The legs 56 are spaced to confine the upper and lower pulleys 51 and 54 to a centered position between the mast plates 37, and to provide spaces between the legs 56 and the inner surfaces of the mast plates 37 for the rearward ends of the side plates 59 of the boom 50.

The boom 50 comprises the elongated side plates 59 having the downwardly offset portions 60 journaled on the upper axle bolt 49 between the yoke legs 56 and the mast plates 37. A web 61 is connected to and between the lower edges of forward portions of the boom side plates 59 to form a rigid structure. Depending ears 62 on the forward ends of the side plates 59 carry between them the boom pulley 63. A depending longitudinal reinforcement 61' on the web 61 has pivoted thereto at 64 the bifurcated upper end of the boom brace 65.

The boom brace 65 comprises spaced side bars 66 suitably connected together for rigidity and terminating at their lower ends, as shown in Figures 12 and 13 in a tubular cylindrical cross-member 67 which spans the width of the space between the mast side plates 37 and can turn and slide vertically between confining front and rear vertical guide strips 68 and 69, respectively, formed on the inward surfaces of the mast side plates 37 near their forward edges 10. In the region of the guide strips the mast side plates 37 have vertically spaced upper and lower holes 71 and 72, respectively, arranged to pass a removable pin 73 which is arranged to pass through the tubular cylindrical cross-member 67 on the lower end of the boom brace 65. With the pin 73 securing the lower end of the boom brace relative to the lower holes 72, the boom 50 is in a horizontal position at right angles to the mast. When higher lift is desired, the lower end of the boom brace is connected to the mast with the pin 73 in the upper holes 71 and the boom 50 then extends forwardly at an upward angle above its

usual horizontal position. Upon disengagement of the pin 73 from the mast, the boom 50 and the boom brace 65 are freed to fall to the inoperative storage position shown in Figure 9, wherein the boom brace 65 is nested between the mast plates 37 and the boom 50 depends along the forward side of the boom brace 65.

Bolts 74, acting to space and connect the mast plates 37, traverse these plates at vertical intervals in vertically aligned rows spaced from the forward and rearward edges of the plates. On the flange 39 on the lower end of the mast 36 is a cam lever operated locking pin device 75 which has a pin 76 arranged to be engaged in one or more holes 77 provided in the socket thrust flange 31 to lock the mast against turning in the socket 30 from a selected position.

A suitable hydraulic pump device, generally designated 79, is mounted on the outside of the right-hand mast plate 37 and has a conduit 79' connected in a suitable manner (not shown), to the hydraulic cylinder 42. An operating handle 80 is provided on the device 79 as well as a let-off valve lever 81.

The hoisting cable 55 terminates at its forward end in a hook 82 to be engaged with the load to be hoisted or with an element to be pulled or stretched. The cable 55 is trained upwardly and rearwardly over the boom pulley 63 and rearwardly and downwardly over the upper mast pulley 51, then forwardly under the hydraulic piston pulley and upwardly to the lowermost pulley 54. The cable is trained rearwardly over the lower mast pulley 54 and then brought downwardly between the pulley 54 and the rear flight of the cable and anchored at 82' to the yoke 47.

It will be apparent from the foregoing that upon operation of the hydraulic pump handle 80 with the valve lever 81 properly set, the piston rod 45, and hence the pulley 48, will be moved downwardly, thereby in effect shortening the cable 55 and moving the hook 82 upwardly in a hoisting action. Resetting the valve lever 81 to open the valve and pulling down on the hook 82 restores the piston rod pulley 48 to elevated starting position, thereby letting the cable hook 82 subside to engage a load.

For lifting low lying objects, the dolly 15 has a lift arm 85 positioned between the legs 16 and pivoted at its rearward end at 86 between depending ears 87 on the forward part of the base plate 17, as shown in Figures 1 and 5. The arm 85 consists of spaced and connected side bars 88 having a rigid bar extension 89 on its forward end including a disc 90 to engage under the load. The arm 85 has an upwardly projecting longitudinal reinforcement 91 intermediate its ends having a hole 92 with which the cable hook 82 is to be engaged. The device is then operated in the usual way to elevate and depress the lifting arm 85.

Referring now to Figures 9 to 11 of the drawings, showing the highway truck mounted form of the invention, it will be understood that the hoisting assembly 35 of this form is identical with that described above, but a different mounting is involved.

In Figures 9 to 11, the mounting takes the form of a socket 30a having a closed bottom 40a and having a relatively wide thrust flange 31a on its upper end. The socket 30a is passed downwardly through an opening (not shown) provided in the bed or platform 93 of the truck 94, preferably at a forward corner thereof near one side edge with the flange 31a resting upon the platform and

bolted or otherwise secured in place, as indicated at 95. The part of the socket 30a depending below the platform 93 is anchored relative to a truck chassis frame side member 96 by braces 97 terminating in an abutment plate 98 having a clamp 99 embracing the socket 30a, as shown in Figures 9 and 10.

The flange 31a of the socket 30a is provided with a plurality of holes 77 for selective engagement by the locking pin 76 of the locking device 75, whereby the hoisting assembly 35 can be locked with the boom 50 pointing in any direction.

Whenever it is desired to use the hoisting assembly 35 on the truck 94, instead of on the dolly 15, the hoisting assembly 35 is simply lifted out of the dolly socket 30, and the spindle 38 inserted in the socket 30a of the truck mounting.

I claim:

1. In a hoist, a support, a perpendicular mast having a lower end seated on said support, a boom having a rearward end pivoted on the upper end of said mast, a diagonal rearwardly declining boom brace having a forward end pivoted to a point intermediate the ends of said boom, said boom brace having a rearward end slidably connected for vertical movement along said mast, means acting between the rearward end of said boom brace and said mast for anchoring the rearward end of said boom brace to said mast whereby said boom is fixed to extend horizontally, a boom pulley on the forward end of said boom, mast pulley means on the upper end of said mast, a vertically movable member having a pulley on its upper end, said vertically movable member being located along the lower part of said mast and in line with said mast pulley means, a cable having a hook on its forward end, said cable depending from and being trained rearwardly over said boom pulley and over said mast pulley means, then downwardly and anchored to said vertically movable member, and operating means for elevating and depressing said vertically movable member to raise and lower said hook.

2. In a folding hoist, a vertical mast comprising a pair of vertically elongated plates, means securing said plates together in laterally spaced relation to each other, a bolt on the upper ends of said plates and extending between said plates, a boom having a rear end pivoted on said bolt between said plates, whereby said boom can be folded downwardly from a horizontal operative position to a folded depending position along the forward side of said mast, said mast plates having vertical guide means extending therealong, a diagonal brace having a forward end pivoted to said boom at a point intermediate the ends of said boom, a crosshead on the rearward end of said brace having ends slidably confined in said guide means whereby the movements of said boom and of said brace between folded and operative positions are guided, and means engageable with said brace crosshead and said mast plates for locking said crosshead in a vertical position along said mast plates wherein said boom is held in a horizontal position.

3. In a folding hoist, a vertical mast comprising a pair of vertically elongated plates, means securing said plates together in laterally spaced relation to each other, a bolt on the upper ends of said plates and extending between said plates, a

boom having a rear end pivoted on said bolt between said plates, whereby said boom can be folded downwardly from a horizontal operative position to a folded depending position along the forward side of said mast, said mast plates having vertical guide means extending therealong, a diagonal brace having a forward end pivoted to said boom at a point intermediate the ends of said boom, a crosshead on the rearward end of said brace having ends slidably confined in said guide means whereby the movements of said boom and of said brace between folded and operative positions are guided, and means engageable with said brace crosshead and said mast plates for locking said crosshead in a vertical position along said mast plates wherein said boom is held in a horizontal position, said brace being narrower than the space between said mast plates whereby said brace can occupy a position between said mast plates in the folded position of said brace.

4. In a folding hoist, a vertical mast comprising a pair of vertically elongated plates, means securing said plates together in laterally spaced relation to each other, a bolt on the upper ends of said plates and extending between said plates, a boom having a rear end pivoted on said bolt between said plates, whereby said boom can be folded downwardly from a horizontal operative position to a folded depending position along the forward side of said mast, said mast plates having vertical guide means extending therealong, a diagonal brace having a forward end pivoted to said boom at a point intermediate the ends of said boom, a crosshead on the rearward end of said brace having ends slidably confined in said guide means whereby the movements of said boom and of said brace between folded and operative positions are guided, and means engageable with said brace crosshead and said mast plates for locking said crosshead in a vertical position along said mast plates wherein said boom is held in a horizontal position, said brace being narrower than the space between said mast plates whereby said brace can occupy a position between said mast plates in the folded position of said brace, hoisting cable means associated with said boom, and hydraulic operating means mounted between said mast plates and connected to said hoisting cable means.
